FRANK C. GROHOSKI, OF SOUTH CHICAGO, ILLINOIS

GAS SAVING DEVICE

Application filed June 19, 1928. Serial No. 286,680.

This invention relates to improvements in carburetor attachments and more particularly to an attachment for installation of the internal combustion engine of an automobile, and one of the objects of the invention is to provide an attachment by the use of which a great saving in gasoline may be effected thus materially reducing the cost of operation of the engine.

Another object of the invention is to provide a carburetor and intake manifold attachment so constructed that a more thorough mixture of the gasoline and air will be effected thereby greatly increasing the efficiency of the engine.

Another object of the invention is to provide an attachment of the class described so constructed that the vaporized gasoline will be thoroughly broken up and intimately mixed with sufficient air to insure of more thorough combustion of the explosive mixture, in the engine cylinders, than is possible by the use of the ordinary carburetor.

While the accompanying drawings and the description which is to follow, constitute a disclosure of the preferred embodiment of the invention, it will be understood that various changes may be made within the scope of what is claimed.

In the accompanying drawings:

Figure 1 is a vertical diametric sectional view illustrating a further modification of the invention.

Figure 2 is a horizontal sectional view taken substantially on the line 12—12 of Figure 1 looking in the direction indicated by the arrows.

Figure 3 is a horizontal sectional view taken substantially on the line 13—13 of Figure 1 looking in the direction indicated by the arrows.

By referring to the drawings it will be seen that the outlet branch of the carburetor bowl is indicated by the numeral 67 and the intake branch of the intake manifold is indicated by the numeral 68, these parts being provided respectively with the usual flanges indicated by the numerals 69 and 70. The attachment, in this embodiment comprises a flat sided plate 71 which is preferably of the same marginal contour as the flanges 69 and 70 and this plate is formed centrally with an opening 72 which substantially registers with the bores of the carburetor outlet branch 67 and the intake branch 68 of the intake manifold, the plate 71 being arranged between the said flanges 69 and 70 and held in place by the usual bolts 73 which are provided for securing these flanges together. A packing gasket 74 is interposed between the flange 69 and the plate 71, and a similar gasket 75 is interposed between the flange 70 and the said plate 71 and this latter gasket 75 is formed with an opening 76 which is concentric to the opening 72 in the plate 71, and a circular sheet 77 of fine wire mesh material is arranged within the opening 76 in the gasket 75 and rests at its peripheral portion upon the upper side of the plate 71 and extends over the opening 72 in said plate, this screen serving the same purpose as the screen 21 of the first described embodiment of the invention.

The butterfly valve of the carburetor is indicated by the numeral 78 and is supported upon the usual rod 79 mounted in the outlet branch 67 of the carburetor, this valve corresponding to the valve 4 in the first described embodiment of the invention. Air passages 80 are formed in the plate 71 and, as shown in Figure 2, extend between the wall of the opening 72 and opposite edges of the plate, these passages providing for the flow of air into the fuel conduit comprising the carburetor outlet branch 67 and intake manifold branch 68 in regulated quantities, as will now be made apparent. The numeral 81 indicates a rod which is mounted for rocking movement at its ends in bearing openings formed in the plate 71 at opposite sides of the opening 72, and arcuate valve plates 82 are fixed at their inner ends as at 83 upon the shaft 81 and close to the wall of the opening 72, and these valve plates extend circumferentially of the wall of the opening and the outer end of each plate normally extends over and closes a respective one of the passages 80. An arcuate finger 84 is united to the shaft 81 at the center of the opening 72 in the plate 71 and is provided

at its free end with a spherical weight 85. By reference to Figure 1 it will be observed that when the valve 78 is in closed position, the weighted end 85 of the finger 84 will rest upon the valve at one side of the stem 79, and in this position of the valve and the rod 81, the valve members 82 will occupy the position shown in Figures 1 and 2, in which position they will close the inner ends of the respective passages 80. However when the valve 78 is opened and the engine is set in motion, the tilting movement of the valve 78 to open or partly open position will relieve the weighted end of the finger 84 of support and therefore this finger will swing downwardly, by gravity, thus rocking the rod 81 and swinging the valve members 82 downwardly clear of the inner ends of the passages 80 thus permitting the intake of air into the fuel conduit 20 to mix with the fuel before its passage to the intake manifold of the engine.

It will be evident that the inventive idea involved is that of arranging a screen in an explosive fluid conducting conduit, together with a baffle, and the provision of means for admitting air into the conduit, it being understood that the screen and baffle and the air inlet ports and controlling valves therefor, need not necessarily be located at the junction of the intake branch of the inlet manifold and the delivery branch of the carburetor, but that this is merely a convenient place to locate the apparatus of the invention.

Having thus described the invention, what I claim is:

1. A gas saving device of the class described, an explosive mixture conduit, means for admitting a gas thereto, a valve within the conduit for controlling the flow of gas 40 through the conduit and supported for tilting movement within the conduit, about an axis diametric to the conduit, a screen in the conduit above the valve, the conduit having an air inlet passageway communicating there- 45 with and with the atmosphere, a rod mounted for rotative movement diametrically of the conduit above the said valve, a valve plate upon the rod extending along the wall of the conduit and adapted to cover and uncover the inner end of the passageway in the rocking movement of the rod, and a finger extending downwardly from the rod and having a weighted lower end resting upon the valve at one side of the axis thereof, the valve con- 50 stituting a means for supporting the finger in an elevated position to maintain the valve plate upon the rod in a position closing the inner end of the passage in the closed position of the valve and the weighted finger con- 55 stituting means for rocking the said rod to move the valve plate to position uncovering the passageway upon opening of the valve.
2. A gas saving device of the class de- 60 scribed, a conduit, an annular body inter- 65 posed in the length of the conduit, the body

having an air inlet opening formed in the side thereof, a valve member pivotally mounted upon the interior of the body and adapted to be swung over said air inlet opening for closing said opening, a gas control valve 70 mounted within the conduit below said body, and means carried by said valve member and engaging said gas control valve for swinging said valve member for opening and closing said air inlet as said gas control valve is op- 75 erated.

3. A gas saving device of the class de- 80 scribed, a conduit an annular body interposed in the length of the conduit, said body having air inlet openings extending transversely therethrough, a shaft extending transversely through the center of said body and constituting a journal, valve members fixedly secured to said shaft and conforming to the contour of the interior of said body and adapted to be swung over said air inlet open- 85 ings for closing said openings at desired pe- 90 riods, a control finger projecting laterally from said shaft and a gas control butterfly valve mounted with said conduit below the body and engaging said finger for moving said finger and consequently said valve mem- 95 bers as said gas control valve is operated.

In testimony whereof I affix my signature.

FRANK C. GROHOSKI.
